UNITED STATES PATENT OFFICE.

EARL RAMSBURG, OF JANELEW, WEST VIRGINIA.

WAITING TABLE.

Application filed February 17, 1923. Serial No. 619,587.

To all whom it may concern:

Be it known that I, EARL RAMSBURG, a citizen of the United States, residing at Janelew, in the county of Lewis and State 5 of West Virginia, have invented certain new and useful Improvements in Waiting Tables, of which the following is a specification.

My invention relates to improvements in 10 tables, the primary object thereof residing in the provision wherein the victuals and other articles supported upon the top thereof may served to the persons positioned at the table, by preferably, the head of the 15 family without the usual necessity of passing these articles by hand, the main portion of the table top being rotatably mounted.

A further object of my invention is the 20 provision of such a table that is comparatively simple of construction and easy of operation, the same consisting of relatively few parts, and these so correlated as to reduce the liability of derangement to a minimum.

The nature and advantages of the invention will be better understood when the following detailed description is read in connection with the accompanying drawings, the 30 invention residing in the construction, combination, and arrangement of parts as claimed.

In the drawings forming part of this application, like numerals of reference indicate similar parts in the several views, and wherein:—

Figure 1 is a top plan view of a table constructed in accordance with my invention.

Figure 2 is a vertical transverse cross sectional view taken substantially upon the line 2—2 of Figure 1.

Figure 3 is a detail cross sectional view upon the line 3—3 of the same figure, and

Figure 4 is a detail cross sectional view upon the line 4—4 of Figure 2.

Referring to the drawings in detail, the numeral 5 designates the table legs, which are formed upon the lower end of a relatively elongated vertically extending housing 6, the opposite ends thereof being open as shown. Substantially centrally of this tube or housing 6, there are formed upwardly extending supporting arms 7 upon the upper ends of which is the table top designated in general by the numeral 8.

The said table top 8 consists essentially of an outer rim portion 9, and a centrally rotary portion 10, the adjacent edges of the rim 9, and the said rotary portion 10 being 30 bevelled as shown more clearly in Figures 2 and 3 and having metallic coverings 11 and 12, respectively. The said bevelled edge of the outer rim 9 is formed with pockets 13, within which are rollers 14, the same 35 projecting slightly outwardly of the pockets and providing bearings for the said section 10.

Upon the bottom face of the section 10, and substantially centrally thereof, is a disk 40 15, the outer periphery being bevelled for engagement within the upper end of the housing 6, this end being also bevelled. The end of the said housing 6 as well as the periphery of the disk 15 have metallic coverings 16, and roller bearings, similar to those disposed between the rim 9, and the central section 10 of the top, this latter mentioned structure not being shown.

Secured at one end to the disk 15 through the medium of nuts 15' is a shaft 17 having its upper threaded end cooperating with said notch, and journaled at its lower end in a cross arm 18 within the tube or housing 6, the extreme end of this shaft carrying a bevelled gear 19. The connection of the threaded end of the shaft 17 with the disc 15 through the nut 15' provides a structure wherein the shaft is adapted to have a limited amount of adjustment relative to the disc for breaking up wear in the bearing and the gears at the lower end of the shaft, and also providing a removable connection with the disc. Beneath the said shaft 17 and journaled at its opposite 55 ends within bearings within the tube or housing 6, is a transversely disposed shaft 20 having keyed adjacent one end a sprocket gear 21, the inner face of which is formed with a bevelled gear 22, for intermesh with the said bevelled gear 19 of the shaft 17. Trained over the said sprocket gear 21 is a sprocket chain 23, which extends outwardly of the tube or housing 6 through an opening 24 and is in turn trained over 60 a sprocket gear 25 upon one end of a shaft 26. This shaft is journaled through one of the before mentioned arms 7 of the table, and carries crank arms 27 at its opposite ends, to which are pivotally secured the upper end of connecting rods 28. The lower ends of these connecting rods are similarly

105

110

pivottally secured to foot pedals 29, they in turn being pivoted as at 30, to the adjacent one of the legs 5 of the table.

In view of the above description, it will 5 be at once apparent that whenever it is desired to rotate the central section 10 of my improved table, the person adjacent the foot 10 pedals 29 may operate these pedals for consequently transmitting motion therefrom to the said section 10.

Although I have herein shown and described the preferred embodiment of the present invention, it is nevertheless to be understood that minor changes may be made 15 therein, without departing from the spirit and scope of the invention as claimed.

Having thus described my invention, what I claim as new, and desire to secure by Letters Patent is:—

20 A self-serving table including a frame having a tube formed with outwardly and downwardly extending legs at the lower end portion thereof and outwardly and upwardly extending table supporting arms from the central portion thereof, said arms terminating in a plane slightly above the upper end of said tube, an outer ring-shaped top section mounted on the upper ends of said arms, the inner edge of said table top section and the 25 upper edge of the tube being formed with inwardly and downwardly inclined beveled portions, a plurality of supporting rollers 30

mounted in said beveled portions, a central annular table top section adapted to fit within the first mentioned section, a disk secured centrally to the lower face of said central table top section, the central top section and the disk each having a beveled edge corresponding respectively with the beveled edges of the outer top section and the upper end of the tube, wear receiving rings mounted on the beveled edges of the central top section and the disk respectively, adapted to engage said rollers and adapted to support said central top section with the upper surface in the same plane as the upper surface of the outer top section in top forming relation, a shaft mounted axially in said tube and rotatable therein having one end 40 removably and adjustably secured to the disk on said top section, and means mounted in the tube and connected with said shaft for rotating the same in the rotation of said means, and means carried by the arms and legs on the outside of the tube for rotating the means within the tube to rotate the shaft and the central section of the table top, whereby the shaft may have limited adjustment relative to the means in the tube without affecting the mounting of the top section and the disk on their respective 45 50 55 60 rollers.

In testimony whereof I affix my signature.
EARL RAMSBURG.
